UNITED STATES PATENT OFFICE.

FRANK J. MOORE, OF NORTH TONAWANDA, NEW YORK.

METHOD AND MACHINE FOR SHREDDING WOOD.

Application filed November 25, 1925. Serial No. 71,474.

- This invention relates to a method and machine for shredding wood, and has for its principal purpose to afford an economical and practical way of treating wood to form fine shreds or fibers in such state as are required for fillers and for producing various compositions, such as artificial wood, plastics, insulating board, wall board and other uses.
- 10 A further purpose of the improvement is to afford a method and mechanism by which wood can be shredded into fine particles of short lengths in place of the wide flat shavings that come from a wood sur-
- 15 facer.
- Still an additional object of the invention is to provide a practical and efficient attachment for a wood planing machine of conventional type using a rotary cutter, so
- 20 that the shavings coming from such machine will be in the form of fine shreds which can be used for a variety of purposes with or without further treatment.
- Another purpose of the invention is to
- 25 afford a method that enables the creation of a valuable by-product from a wood surfacing machine and thus substantially reducing the cost of operation of the latter.
- With these and other ends in view, the
- 30 invention comprises the structure that will appear clearly from the following description when read in conjunction with the accompanying drawings, the novel features being pointed out in the claims following
- 35 the description.
- In the drawings:
- Figure 1 is a side elevation of a conventional type of wood planer or surfacer, illustrating the application thereto of a
- 40 possible embodiment of the invention;
- Figure 2 is an enlarged side view of the parts forming the attachment for slitting the board;
- Figure 3 is an end elevation of the same;
- 45 Figure 4 is a sectional view taken vertically through the slitting rolls;
- Figure 5 is a plan view;
- Figure 6 is a sectional view on the line 6—6 of Figure 2, and
- 50 Figure 7 is a detail perspective view of one of the adjustable bearings for the slitting rolls.
- The invention may be carried out in a variety of ways, and in the embodiment
- 55 shown, it is applied to a conventional type of wood planer designated generally at 1,
- and including a rotary planing cutter 2. In the operation of planing a board, such a machine takes successive short cuts from the work as the tools on the rotary cutter engage and disengage the surface of the board, resulting in short but wide shavings. One practical and successful way of carrying out my method resides in applying to such a planing machine an attachment
- 60 that slits the surface of the board before it is planed, preferably during its travel through the planer. The preferred way of doing this is to employ a rotary slitting roll
- 65 in advance of the planing cutter.
- 70 In the mechanism disclosed, 3 and 4 designate upper and lower slitting rolls mounted on shafts 5 and 6 which are mounted in adjustable bearings 7. Bearings 7 have side guides 8 which engage guideways 9 in the uprights 10. The upper bearings carry threaded posts 11 operated by nuts 12, the nuts 12 being provided with worm gears 13 that are operated by worms 14 on the adjusting spindle 15. The lower bearings 7 are
- 75 elevated or lowered through eccentrics 16 on the adjusting spindle 17. In this way, the slitting rolls 3 and 4 can be adjusted to accommodate boards of different thicknesses, or to vary the pressure on a board, as well
- 80 as the depth of cut by the knives 18 carried on the slitting rolls. There may be both upper and lower slitting rolls or only a single roll, depending on whether the board is to be planed on one or both sides, and the roll
- 85 spindles 5 and 6 carry pulleys 19 and 20 for engagement by a belt 21 operated from the power pulley 22, as shown in Figure 1. It is
- 90 obvious, however, that other arrangements of slitting rolls and driving instrumentalities
- 95 may be used without changing the essential features of the method or function of the machine.
- Figure 5 shows a board passing between the slitting rolls and before reaching the planing cutter, the forward part of the board beyond the slitting rolls being prepared by the latter for the planing operation. This is also illustrated in Figure 4, which shows a slit in the surface of the board to a depth that will be planed off when the planing knife is reached. I am aware of the various types of machines proposed and used for making excelsior, or wood wool, but in these, the planing operation is one of a reciprocatory relation between the knife and the stock, resulting in
- 100
- 105
- 110

- long shavings or stringy coils, which are unsuited for the uses of my invention without further treatment. To enable the use of excelsior for such purposes necessitates 5 grinding the mass, whereas with my method, the shreds or fibers are of such short lengths that they require no further cutting when used with a binder for making products such as insulating and wall board and the like.
- 10 The principal advantage of the invention is that the product can be obtained from a conventional wood planer with the usual planing operation, and without affecting the finished product of the planer. The 15 lumber is dressed and sold commercially the same as heretofore, and my invention changes only the resulting by-product as it comes from the commercial planer. A separate machine is unnecessary, and the 20 shredded mass is produced from seasoned lumber such as is ordinarily fed to a planing machine, as contrasted with wood wool that is made from green lumber. A mechanism such as described causes the shavings 25 from the planer to be in the form of very fine shreds of approximately one to three quarters of an inch in length, depending upon the arc of movement of the cutting tools.
- 30 The slitting knives and cuts formed thereby in the board may be arranged otherwise than as shown, and the operation of slitting the surface of the board may be carried out on a machine separate from the 35 planer if desired. This as well as other

modifications and changes may be adopted without departing from the underlying features of the invention or the scope of the following claims.

I claim:

1. The method of shredding wood which consists in slitting the surface of a board longitudinally and then feeding it endwise to a cylindrical planing cutter with circumferentially spaced knives which intermittently engage said slotted surface and produce short, fine shreds. 40
2. The combination with a wood planer including a cylindrical rotary cutter having circumferentially spaced knives, of means attached to the planer for slitting the surface of a board longitudinally before the latter reaches the planing cutter. 45
3. The combination with a wood planer including a cylindrical rotary cutter having circumferentially spaced knives, of mechanism arranged in advance of the cutter and acting to form a series of longitudinal slits in the surface of a board before it reaches the planing cutter. 50
4. The combination with a wood planer including a cylindrical rotary cutter having circumferentially spaced knives, of a slitting roll arranged in advance of the planing cutter and acting to form a series of longitudinal slits in the surface of a board before it reaches the planing cutter. 55

In witness whereof, I have hereunto signed my name.

FRANK J. MOORE.
